Primary Examiner—Holly H. Baynham
Attorney, Agent, or Firm—Laura J. Zeman[57] **CLAIM**

The ornamental design for an angled three coat plastering corner support, as shown.

DESCRIPTION

FIG. 1 is a perspective view of the angled three coat plastering corner support showing my new design taken from the back of the angled three coat plastering corner support;

FIG. 2 is a side elevational view thereof;

FIG. 3 is a top plan view thereof;

FIG. 4 is the opposite side elevational view thereof; and,

FIG. 5 is a bottom plan view thereof.
